[57] CLAIM

The ornamental design for a window fan or the like, as
shown and described.

DESCRIPTION

FIG. 1 is a top front and right side perspective view of
a window fan or the like showing our new design;
FIG. 2 is a left side elevational view thereof;
FIG. 3 is a top plan view thereof; and,
FIG. 4 is a bottom plan view thereof.
The rear of the design is flat and unornamented.
